SHELF PEG OR REFRIGERATOR HOOK

Filed Jan. 20, 1928

UNITED STATES PATENT OFFICE

EDWIN W. NORTH AND ROY E. LARSON, OF ROCKFORD, ILLINOIS, ASSIGNEES TO NATIONAL LOCK CO., OF ROCKFORD, ILLINOIS, A CORPORATION OF DELAWARE

SHELF PEG OR REFRIGERATOR HOOK

Application filed January 20, 1928. Serial No. 248,118.

This invention relates to pegs in general and more particularly to shelf pegs of the type used in refrigerators.

Pegs of the type generally in use for supporting refrigerator shelves have been so constructed that it was necessary to attach them to the refrigerator lining prior to its assembly in the refrigerator cabinet and after such assembly they could not be tightened if they became loose.

The primary object of this invention is accordingly to improve upon pegs generally in use and to provide a shelf peg capable of being used in connection with refrigerators or the like in which the peg may be tightened after assembly of the refrigerator.

Another object of this invention is to provide a peg of this type which is of considerable strength yet is simple of construction and economical of manufacture and assembly.

Other and further objects of this invention will be apparent as the same becomes better understood from an examination of the specification and claims in connection with the accompanying drawings wherein:

Fig. 1 is a fragmentary front elevational view showing a refrigerator lining having attached thereto a shelf peg embodying this invention.

Fig. 2 is a sectional view taken at the line 2-2 of Fig. 1.

Fig. 3 is a perspective view of the shelf peg with parts omitted.

Fig. 4 is a fragmentary elevational view taken from the outside of the refrigerator compartment lining, and

Fig. 5 is a fragmentary elevational view taken from the outside of the refrigerator compartment lining showing a modified form 40 of aperture for the peg provided in the lining.

Referring to the drawings more particularly, numeral 6 represents the sheet metal lining of the food compartment of a refrigerator.

The lining 6 is provided with a pair of vertically spaced apertures 7 and 8, respectively, to support a shelf peg represented generally by the number 9.

50 The peg 9 is preferably made by upsetting

one end of a section of elongated cylindrical stock to provide a flat laterally extending integral head 11. The head 11 is provided with a tapped hole 12 spaced from the shank 13 of the peg. The inner end of the peg is 55 bent to form the hook portion 14.

The peg 9 projects through the aperture 7 and a screw 15 extends through the aperture 8 into threaded engagement with the hole 12 for clamping the head 11 against the lining 6, a spring washer 16 preferably being used between said lining and screw to prevent the same from working loose and to seal the apertures 7 and 8.

In the process of assembly the peg is 65 inserted from the outside of the lining 6 and is attached thereto before the lining is assembled in the refrigerator. Should the peg become loose the lining need not be disassembled as in the use of the ordinary pegs but 70 it may be tightened by merely turning the screw 15 from inside the refrigerator compartment.

In Fig. 5 there is shown a modification in which the lining 6 is provided with a horizontally elongated aperture 17 in place of the aperture 7 so that the pegs may be renewed entirely after the lining 6 has been assembled, the aperture 17 permitting the passage of the head 11 through the lining from the inside to 80 the outside thereof.

We are aware that many details may be varied throughout a wide range without departing from the principles of this invention and we therefore do not wish to be limited to 85 the details shown and described.

We claim:

1. The combination with a wall of a cabinet, one side of which is normally inaccessible, of a peg adapted to be rigidly secured 90 to and supported by said wall, said wall having a plurality of spaced apertures, said peg adapted to extend through one of said apertures and having a base flange adapted to engage the inaccessible side of said wall to 95 overlie another of said apertures and a securing device insertable through said other aperture from the accessible side of said wall and adapted to engage said base flange for 100 securing the same in place.

2. The combination with a wall, one side of which is normally inaccessible, of a peg adapted to be rigidly secured to and supported by said wall, said wall having a plurality of spaced apertures, said peg adapted to extend through one of said apertures and having a base flange adapted to engage the inaccessible side of said wall and to overlie another of said apertures, a securing device 5 insertable through said other aperture from the accessible side of said wall and adapted to engage said base flange for securing the same in place and a sealing plate surrounding said peg and securing device and held in engagement with said wall by said device.
3. The combination with a wall having a pair of spaced apertures therein, of a peg comprising a section of elongated stock having an end thereof upset to provide a flat laterally extending integral head, said head having a tapped aperture for the reception 10 of a threaded securing device and being adapted to be inserted through one of said wall apertures and to engage said wall adjacent the aperture through which it passes with the tapped aperture overlying the other of said wall apertures and a securing device insertable through said other wall aperture and engageable with the tapped aperture for 15 holding said head in place.
4. The combination with a wall having a pair of spaced apertures therein, of a peg comprising a section of elongated stock having an end thereof upset to provide a flat laterally extending integral head, said peg 20 being adapted to extend through one of said apertures on one side of said wall with said head in engagement with the other side of said wall, said head having a threaded bore 25 in alignment with said other aperture, a sealing plate adapted to engage the side of said wall opposite to said head, said plate having an aperture snugly fitting the shank of said peg and a second aperture in alignment with 30 the other wall aperture and threaded bore and a securing device extending through said apertures and engaging said threaded bore, said device serving to clamp said parts in assembled relation and also to seal the said second aperture in said sealing plate.

In witness of the foregoing we affix our signatures.

EDWIN W. NORTH.
ROY E. LARSON.
